(57) **CLAIM**

The ornamental design for a wheel, as shown and described.

DESCRIPTION

FIG. 1 is a left front perspective view of a wheel in accordance with the claimed design;

FIG. 2 is a front elevation view of the design of FIG. 1; FIG. 3 is a rear elevation view of the design of FIG. 1; and, FIG. 4 is a side elevation view of the design of FIG. 1.

The dash-dash broken lines in the figures represent unclaimed subject matter and form no part of the claimed design.

The dot-dash broken lines in the figures immediately adjacent solid lines represent a boundary between claimed and unclaimed subject matter and form no part of the claimed design.

1 Claim, 4 Drawing Sheets(56)
